CLAIM

The ornamental design for a plastic mold, as shown.

DESCRIPTION

FIG. 1 is a bottom view of a plastic mold showing my new design;

FIG. 2 is a cross sectional view taken along line 2—2 of FIG. 1;

FIG. 3 is a top view thereof;

FIG. 4 is an end view thereof;

FIG. 5 is a side view thereof;

FIG. 6 is a side view thereof opposite FIG. 5;

FIG. 7 is an end view thereof opposite FIG. 4;

FIG. 8 is a bottom view of a plastic mold showing an alternate embodiment of my design;

FIG. 9 is a cross sectional view taken along line 9—9 of FIG. 8;

FIG. 10 is a top view thereof;

FIG. 11 is an end view thereof;

FIG. 12 is a side view thereof;

FIG. 13 is a side view thereof opposite FIG. 12; and,

FIG. 14 is an end view thereof opposite FIG. 11.
